DEVICE FOR SEPARATING CARBONACEOUS MATERIALS

Joel R. Belknap, South Charleston, W. Va.

Application July 27, 1937, Serial No. 155,958

4 Claims. (Cl. 209—157)

The invention relates particularly to mechanism adapted for separating carbonaceous materials. My copending application Serial Number 48,388 is intended for similar purposes. Heretofore many different methods and kinds of apparatus and mechanism have been used for separating coal from slate, and other refuse in coal, some of which utilize the differences in specific gravities in the component parts of the aggregate 5 run of mine coal. Others of them utilize a liquid having a relatively high specific gravity, whereby the relatively light weight coal will float on the surface and the heavier slate and other refuse will sink to the bottom of the liquid, because the 10 specific gravity of the liquid is greater than the specific gravity of the coal but less than the specific gravity of the slate and other refuse. Such methods which utilize this latter method, known as floatation processes, are slow in operation and the cost of equipment and subsequent 15 operation is relatively high.

Other classifications of methods and apparatus are utilized to effect a separation of coal from slate, and other refuse in coal, by passing a current of water through compact masses of coal, causing the heavier slate and refuse to segregate and collect at the lower part of the whole mass, from which they are separated by specially 20 designed mechanism. However, in many such methods the separation is not as effective as in my method, and by use of my apparatus.

From experimentation and actual practice, I have determined that the relative differences in the velocities of sinking components of coal and 25 refuse is greater than indicated by a mathematical comparison of the specific gravities and velocities of sinking coal and refuse. For illustration, if a piece of coal which has a specific gravity of 1.4 is placed in water, the force acting to sink the coal is proportional to 1.4 less 1.0, or .4. If the coal is placed in a liquid having a specific 30 gravity of 1.2 the sinking force is proportional to 1.4—1.2, or .2 which is half the force acting to sink the coal in water. Similarly consider refuse 35 (for example slate) having a specific gravity of 2.6, the sinking force in water is 1.6 and in liquid having a specific gravity of 1.2 is 1.4. Thus the sinking ratio as between refuse and coal would be 40

$$50 \quad \frac{1.6}{0.4} = \frac{4}{1} \text{ in water and } \frac{1.4}{0.2} = \frac{7}{1}$$

in a liquid of 1.2 specific gravity. This larger ratio favors clean separation, particularly where the forms and specific gravities of the granules to be separated are subject to variation. How-

ever, actually the difference, when compared with coal and refuse, is appreciably greater, because refuse, such as slate, usually is flat or streamline, whereas coal usually is of cubical shape, or somewhat spherical.

Using the term "rising current classification" as meaning classification effected through the different settling rates of granular particles of different specific gravity, (or of different shape and specific gravity) in a rising stream of liquid, it 5 will be observed that the differentiation of settling rate can be intensified by using a liquid whose specific gravity is less than, but only moderately less than the specific gravity of the particles of lower specific gravity. This concept 10 is an important feature of the present invention. Strict flotation requires solutions too concentrated for successful commercial use, but it is entirely practicable to use the relatively dilute 15 solutions needed for a rising current process. 20

My invention differs particularly from the floatation methods because I utilize a liquid having a specific gravity less than the lightest component of coal. Therefore, my liquid has a specific gravity of less than the heavier components slate and other refuse. My utilized liquid ranges in specific gravity from a maximum point which is less than the specific gravity of the lightest component of uncleared coal to a minimum determined by economic considerations 25 affected by the problem of maintaining the concentration of the solution, etc., for the device will 30 operate with water, but not so advantageously.

Another important difference between my process and apparatus and the past art is that the 35 coal, as it comes from the mine, is not treated in a mass, but each piece of coal or refuse, or piece of coal containing refuse, is acted upon separately and sinks in an individual path depending on its size, specific gravity and shape. In other words, 40 the device operates on the rising current principle, and is sharply distinguished from a jig.

Also, I provide a container for said liquid which has two compartments, communicating with each other. One of said compartments contains refuse 45 and the other said compartment contains sinking coal and refuse. I control the sinking velocity of the coal and refuse, as slate, by providing adjustable means which can be regulated to vary the velocity of upward currents of liquid from one 50 compartment and into the other and through which currents coal and refuse is sinking and, at the same time, cross or transverse currents are produced in the liquid in one of said compartments for the purpose of transporting the coal,

which sinks at a lesser velocity than the refuse, to a predetermined area or to mechanism adapted to convey the pure coal from the liquid and from the container in which the liquid is contained, 5 and simultaneously the refuse, which is in a different area in the liquid and container, is conveyed by suitable mechanism from the liquid and container.

Therefore, the important objects of the invention are to provide a simple, efficient, and practical method, and mechanism to carry out said method, for separating coal from slate and other refuse in coal by allowing the particles to sink through two currents which combine to create a 10 current of liquid which moves vertically and horizontally, said liquid being lighter in specific gravity than the lightest component of the aggregate whereby the heavier components shall deposit in a predetermined space and the lighter 15 components shall deposit in a different space; to provide mechanism to convey said coal and slate; and to provide means to produce upward and horizontal currents of said liquid and to regulate the velocity of said currents.

25 Other objects of the invention are apparent by reference to the hereinafter description, and drawings.

The invention consists in the combination of the elements, arrangement of the parts and in the 30 details of the construction, as hereinafter fully explained.

In the drawings:

Fig. 1 is a side view of the container, and mechanism with parts broken away, having the 35 invention incorporated therein;

Fig. 2 is a plan view of the same, with parts broken away, and showing the invention incorporated therewith;

Fig. 3 is a section taken on a line corresponding 40 to 3—3 in Fig. 2 with parts broken away;

Fig. 4 is a section taken on a line corresponding to 4—4 in Fig. 1, with parts broken away;

Fig. 5 is a section taken on a line corresponding to 5—5 in Fig. 1;

45 Fig. 6 is a fragmentary side elevation at the discharge end of the tank, with parts removed and broken away, showing the mechanism for controlling the flow of water and solution;

Fig. 7 is a side elevational view of a sprocket, or 50 pulley, and conveyor, with parts broken away;

Fig. 8 is a diagrammatic view of the conveyor drives; and

Fig. 9 is a plan view of the valve mechanism, and tank with parts broken away.

55 In the preferred construction of the invention I provide the tank or container 1 which is supported by the platform 2, and supports 2'.

The tank 1 has a horizontal bottom 3 and vertical side walls 4 and 5 rising from the bottom 60 and integrally connected therewith. The inlet end wall 6 inclines upwardly and outwardly at an obtuse angle with respect to the bottom and is integrally connected with the side walls 4 and 5. The outlet end wall 7 is integrally connected 65 with the bottom and side walls.

Formed in the bottom 3, of the tank 1, is the trough 8 which extends transversely and across the tank. The width of the opening 9 of the open top of the trough and its location is predetermined by calculation and in consideration of all the factors involved in the operation of the invention. As will be hereinafter explained the trough 8 receives the heavier or impure components of the mined coal, as slate, rock, and other 70 impurities, which will be referred to as refuse 9,

which are separated from the pure coal 10. A screw conveyor 11 is positioned in and operates in the trough 8 to convey the refuse to the outside of the tank 1. The shaft 12, which revolves the conveyor 11, has one end 13 journaled in the end 5 wall 14 of the trough 8.

On the side wall 4 of the tank 1 is secured a conveyor casing 15 and the lower end thereof opens into the discharge end 16 of the trough 8. The casing 15 is inclined upwardly from the trough 8 to the discharge end of the tank, and forms a water-tight chamber from the trough 8 to a point above the liquid level in the tank where it is open to receive the endless refuse conveyor 17 which travels in the casing 15. The screw conveyor shaft 12 has an extension on the end 18 journaled in the end wall 19 of the trough 8. On this extension is rotatably mounted the lower sprocket pulley 20 about which the lower end of the refuse conveyor belt 21, of the conveyor 17, 20 is trained. There are transverse cleats 22 on the conveyor belt 21 which wipe against the bottom inclined wall 23 of casing 17 and slide the refuse 9 up the inclined wall 23. The refuse is pushed into the casing 17 by the screw conveyor 25 11. The conveyor conveys the refuse up the bottom of the casing and discharges this refuse into the chute 24 which is separate from the discharge chute 25 for the coal 10.

The shaft 26 is journaled in a bracket 27 at one 30 end and in the bracket 28 at the other end. This shaft 26 has a pulley 28 thereon similar to the pulley 20, and about this pulley 28 is trained the upper end of the refuse conveyor 17.

Fixed to the upper end of the discharge end 35 wall are aligned bearing brackets 29 and 30 in which are journaled the ends of the shaft 31, on which is secured a sprocket pulley 32, around which is trained the upper end of the endless coal conveyor 33. The shaft 31 drives the coal conveyor 33 in a direction opposite to the refuse conveyor 17. The lower coal conveyor sprocket pulley 34 is fixed to a shaft 35, the ends of which are journaled in the side wall 5 of the tank. The conveyor 33 is perforated and has substantially 45 the same width as the tank 1.

As the pure coal 10 sinks through the liquid 34 in the tank 1 it deposits on the upper flight of the conveyor 33 at the lower end, as will be herein-after explained, where it is carried upwardly on 50 an incline and discharged over end wall 7 and into the coal chute 25, at a point separate from the refuse.

Extending transversely of the tank 1, at the discharge end of the tank, and supported in suitable brackets is a water pipe 36 apertured at points over the tank. Water is sprayed on the coal from this pipe 36 as the coal emerges from the tank and the coal is washed. Moreover, a portion of the liquid 34 which adheres to the coal is thereby 60 returned to the tank.

For the purpose of causing an internal movement of the liquid 34 in the tank 1 an apron or bridge wall 37 is provided which extends across the tank with flanges 38 on the sides thereof 65 bolted to the side walls 4 and 5 of the tank. The bridge wall is located at the end of the conveyor 33 and above the vertex of the obtuse angle formed between the outlet end wall 7 and the bottom 3 of the tank. The impeller chamber 39 is formed as by the end wall 40, and the upper and lower horizontal walls 41 and 42. The end 43 of the wall 41 is connected with the bridge wall 37 and the end 44 of the wall 42 is connected with the outlet end wall 7. The other ends of the 70

walls 41 and 42 have connected therewith the vertical end plate 45 in which is journaled the propeller shafts 46 and 46' having fixed to their ends 47 the propellers 48 and 48'. The other end 5 of the shaft 46 has a wheel 49 and a pulley 50 fixed thereto. The wheel 49 is in contact with the wheel 51 which is connected with and operated by the usual electric motor 52 supported by the support 53 which is mounted upon the platform 2.

The shaft 46' has a pulley 50' thereon which is in alignment with the pulley 50 whereby a belt 53 causes rotation of the shaft 46' and pulley 50', when the wheel 51 imparts rotary movement to 15 the wheel 49, shaft 46 and propeller 48.

In relatively small tanks only one impeller is necessary but in the apparatus illustrated a pair of propellers are shown. An intermediate portion 20 of the impeller shafts 46 and 46' are journaled in water-tight bearings 54, in the end plate 45, and the outer portion of these shafts extends outwardly of the tank.

The tank 1 has two compartments, the upper compartment 55 and the lower compartment 56. 25 The compartments are divided by the partition 57 which comprises the buttress plate, or side, 58, the apron or bridge wall 31, and the upper flight of the conveyor 33 which has the spaced apart perforations 59 therein to permit liquid to 30 drain from the coal into the tank 1. The opening or separating slot or passage 60 is provided in the partition 57 and which is a passage for refuse, as will be hereinafter explained.

For the purpose of insuring that the heavier 35 components of the aggregate will fall into the trough 8, in the event that there is not complete coordination of the operating elements, such as sudden changes in the rate of raw coal feed, specific gravity of the liquid, or other such factors, the buttress plate or side 58, which bridges the width of the tank 1, is positioned adjacent the inlet end wall 6 and arranged to swing on horizontal pivot bolts 61, one for each side of the plate. The ends of these bolts are anchored to 40 the side walls 4 and 5. These bolts 61 extend through apertured ears 62 fixed to the upper corners of the plate. The plate 58 extends the major portion of the depth of the tank and terminates at a point substantially in alignment with the upper half of the bottom sprocket pulley 20 so as 45 to be aligned with the lower end of the upper flight of the conveyor 17. All coal and refuse falling on the plate 58 are directed toward the passage 60.

The angle of plate 58 may be adjusted by the 55 use of a bolt 63 having a threaded intermediate portion extending through a slightly elongated aperture in the end wall 6 and threadably engaged by a pair of nuts 64, one bearing on each side of the end wall 6. The inner end of the bolt 63 extends through an opening in the plate 58. A pair of nuts 65 are mounted on the inner end of the bolt 63, one bearing on each side of the plate 58. Thus by changing the gripping positions of 60 the nuts 64, the angle of the plate 58 may be changed as desired.

Fixed to the lower end of the wall 40 is the plate 40' which has a plurality of slots 40" therein. The plate 40' is inclined downwardly and toward 65 the outlet wall 7.

Due to the rotatable movement of the propellers 48 and 48', the liquid is caused to move, and a current is created in the liquid. For the reason that the partition 57 separates the tank into two 70 compartments 55 and 56, and the current of liquid

is created in the lower compartment 56, this current must travel through the perforations 40" in the plate 40', and below the plate 40' and then upwardly through the passage 60 at a rate of speed dependent, and capable of being regulated, upon the revolving speed of the propellers 48 and 48' and the width or area of the passage 60. The position of the hinged plate 58 controls the area of the passage 60, w. hereby if the plate 58 is raised the area of the passage is reduced and the velocity of upward current of liquid, in consideration of the propellers having a regular rotatable speed, is increased. On the other hand, if the plate 58 is lowered the area of the passage 60 is increased and, since the area of the path of the current of liquid is increased, the speed or velocity of the current is decreased. Obviously, with the passage 60 having a predetermined area, or width and length, the velocity of the current of the liquid which passes upwardly through the passage 60 can be increased or decreased by varying the rotatable speed of the propellers.

Now it is obvious that not all of the currents, or agitated liquid, pass through the passage 60, whereby a secondary current of the liquid travels past the passage 60 and contacts the inlet wall 6 and is deflected upwardly and in contact with the plate 58. This latter mentioned or secondary current carries liquid through the perforations 65 in the plate 58 and after this secondary current passes through the perforations, and through the coal and refuse on the plate 58, this secondary current drifts or moves horizontally or toward the outlet end 7 of the tank 1 and meets the upward current which previously has passed through the passage 60. The meeting of the upward current with the horizontal current produces a current or drift of the liquid in a direction which is substantially at an angle upwardly and toward the outlet wall or end 7 of the tank.

Since the specific gravity of the pure coal is only moderately greater than the specific gravity of the liquid, the lifting effect of the upward current of liquid keeps the coal in suspension for a considerable time. This action can be modified by varying the specific gravity of the liquid or by varying the velocity of the rising current, but in any event, the coal which remains in suspension after it leaves the supply chute is kept in suspension until the cross-current produced by flow through the perforations 65 in the plate 57 carries the coal over the barrier 31. Refuse settling on the plate 57 will slide to the throat, and if any coal should be trapped with the refuse and slide with it to the throat it will be elevated by the rising current and carried over the barrier 31. Consequently, while the separation occurs almost exclusively with the coal in suspension, any coal which may move to the throat over the plate 57 together with the settling refuse, will be recovered by being again brought into suspension in the zone where the rising current of liquid is most active.

The liquid 34 substantially fills the tank to the level indicated at 67. This liquid may vary in specific gravity within the limits of pure water and a liquid having a specific gravity equal to the specific gravity of the lighter component coal. When it is desired to increase the specific gravity of the liquid above water any of the cheaper grades of salts that will not disintegrate the coal or adversely effect its burning properties may be used. Common salt or sodium chloride has been used with excellent result, as well as calcium chloride, magnesium chloride, or any of the salts

of the alkali earth metal group taken separately or in combinations, depending on their relative economy and desired effects.

It is, of course, advantageous to maintain a substantially constant predetermined density or specific gravity of the liquid in tank 1 and to compensate for the volume absorbed by the refuse 9 and the coal 10, salt or other materials heretofore mentioned is automatically introduced for increasing the density, either in granular or concentrated liquid form through conveyor pipe 68 by any suitable pressure, gravity or otherwise. This pipe 68 deposits the liquid or granular material in the tank above the liquid level 67 thereof. In the pipe 68 is a control valve 69 having a lever 70 to turn the valve.

On the wash-water pipe 36 there is a control valve 71 outwardly of the perforated end that is positioned over the tank. On one side wall 4 of tank 1 is a bracket 72 to which is pivoted as at 73 the apex of a bell crank lever and one leg 74 of this lever is formed with a series of openings 75 continuous with its length. The other leg 76 of this lever has the free end pivoted at 77 to an upstanding arm 78 on the float 79. The float moves as the liquid level 34 in the tank varies.

The valve arm 70 is connected by a link rod 80 to any predetermined point on the arm 74 by a bolt 81 inserted in the selected opening of the series 75. The valve 71 is likewise connected by a link rod 82 by means of a bolt to any one of the series of openings 75 on the arm 74. The variation of the liquid level is therefore transmitted through the float 79, the bell crank 76, link rods 80 and 82, to the water valve 71 and the density increasing material pipe valve 69. Since the stroke of the link rods 80 and 82 may be regulated, and these link rods move in response to the variation of the liquid level in the tank, the volume of water and the density increasing material may be controlled.

Any suitable means may be used to drive the conveyors 33 and 17, and in Fig. 2 is shown the electrically operated motor 83 which has the driving shaft 84 on which is connected the gear 85 and the sprocket 86. On the sprocket 86 is meshed the chain 87 which is meshed with the sprocket 88 fixed to the shaft 31 which operates the conveyor 33 by means of the sprockets 32.

Fixed to the end of the shaft 84 is the gear 85 which meshes with the gear 89 fixed to shaft 90 which is fixed to the casing 15, as by the bolts 91 and 92. On the shaft 90 is the sprocket 93 on which is meshed the chain 94 which also meshes with the sprocket 85 fixed to the shaft 96 which has sprockets thereon that operate the conveyor 17.

It is, therefore, quite apparent that I have invented a highly desirable device for the heretofore fully described purposes and which may be utilized to separate carbonaceous materials efficiently, dependably, and economically. Furthermore, the simplicity of the invention enables and assures its economical manufacture and, at the same time, minimizes possibility of the various parts of the invention getting out of order or developing defects which are likely to prevent its usage or lessen its efficient operation.

While I believe that the form of the invention illustrated in the drawings and referred to in the above description, as the preferred embodiment, is efficient and practical, yet realizing that the conditions concurrent with the adoption of the device will necessarily vary, I desire to emphasize the fact that changes in the details may

be resorted to, when required, without sacrificing any of the advantages of the invention as defined in the claims.

For example, the impure or mined coal may be fed onto the plate 58, and into the tank 1 by any kind of conveyor or feeding device. The pure coal conveyor 33 may be any conventional design, such as a single or double chain with open metal flights. The refuse conveyor 17 may be a ram or plate feeding to an elevator of either screw or bucket type, or flight conveyor. The circulating propellers may be placed at different angles to the position shown to favor various conditions of installation, in which cases suitable housing or casing may be used. The speed of the propellers may be adjusted by any variable speed transmission device other than those shown, or the speed-changing devices may be discarded when the best speed for a particular constant operating condition is determined. Furthermore, the design of the plate 58, as well as the partition 57 may be changed to meet various conditions.

What I claim as new and desire to secure by Letters Patent is:

1. In a device for separating mixtures of granular solids having different settling rates through a liquid and characterized by different specific gravities, the combination of a tank containing a liquid whose specific gravity is greater than one and only moderately less than the solid of lower specific gravity said tank having an entrance side; a barrier extending across said tank approximately parallel with said entrance side with its top substantially horizontal and below the liquid level in the tank and its lower margin above the bottom of the tank; a foraminous guide partition sloping downward from approximately the liquid level along the entrance side of the tank toward the lower margin of said barrier from which it is spaced horizontally, the lower margin of the guide partition being formed to produce with the barrier a narrow approximately vertical throat; means for circulating liquid in the tank from the space beyond the barrier beneath the barrier and then upward, part passing upward through said throat and part upward through said foraminous guide partition, the structure being so arranged that the guide partition delivers any solids sliding down it into the throat and the liquid flowing upward through the guide partition flows with a substantial horizontal component toward the stream of liquid rising through the throat, and joining therewith, flows over the barrier; means for feeding solids to be separated to the guide partition at the entrance side of the tank; means for intercepting and withdrawing the lighter granular solids which tend to settle in that part of the tank beyond the barrier; and other means for collecting and withdrawing from the bottom of the tank the heavier granular solids which settle through said throat.

2. In a device for separating mixtures of granular solids having different settling rates through a liquid and characterized by different specific gravities, the combination of a tank containing a liquid whose specific gravity is greater than one and only moderately less than the solid of lower specific gravity, said tank having an entrance side; a barrier extending across said tank approximately parallel with said entrance side and inclined upwardly and away therefrom with its top substantially horizontal and below the liquid level in the tank and its lower margin above the

bottom of the tank; a foraminous guide partition sloping from approximately the liquid level along the entrance side of the tank downward toward the lower margin of said barrier from which it is spaced horizontally, the lower margin of the guide partition being formed to produce with the barrier a narrow throat; means for circulating liquid in the tank from the space beyond the barrier, beneath the barrier and then upward, part passing rapidly upward through said throat and part less rapidly upward through said foraminous partition, the structure being so arranged that the guide partition delivers any solids sliding down it into the throat and the liquid flowing upward through the guide partition flows with a substantial horizontal component toward the stream of liquid rising through the throat, and joining therewith, flows over the barrier; means for feeding solids to be separated to the guide partition at the entrance side of the tank; means

for intercepting and withdrawing lighter solids which tend to settle in that part of the tank beyond the barrier; and other means for collecting and withdrawing from the bottom of the tank solids settling through said throat.

5

3. The combination defined in claim 1 in which the lower end of the guide partition is imperforate and curved downwardly and in which the barrier is curved at its upper portion away from the entrance side of the tank whereby the upper end of the throat formed between the guide partition and the barrier is gradually flaring and consequently adapted to minimize eddying while favoring horizontal flow away from the entrance side over the top of the barrier.

10

4. The combination with the structure defined in claim 1 of means for so adjusting said guide partition relatively to said barrier as to vary the width of the intervening throat.

15
